T. DE LA MARE

RAILROAD TIE

Filed Nov. 3, 1925

Inventor

THOMAS DE LA MARE,

By A. Mallinckrodt
Attorney

UNITED STATES PATENT OFFICE.

THOMAS DE LA MARE, OF SALT LAKE CITY, UTAH.

RAILROAD TIE.

Application filed November 3, 1925. Serial No. 66,559.

This invention relates to a cross tie for railroad tracks and the like, and its principal objects are:

First. To provide a tie which shall be much more durable than the usual wooden tie, though still preserving the desirable characteristics of wood.

Second. To make such a tie with a portion to take the wear, the said portion being easily and cheaply replaceable.

Third. To provide a cushioning member upon which the rail may be supported to prevent crystallization of the metal of the tie due to pounding of wheels upon the rails.

15 Fourth. To make a tie of the kind stated which shall have easily manipulated means for securing the rail firmly upon the tie.

Fifth. To reduce the cost of maintaining railway tracks in good condition by means of 20 a tie that will require attention at very long intervals only.

Sixth. To produce a tie that, due to its simplicity, shall be adapted to quantity production and therefore to economical manufacture.

The wooden ties used in railroad and other tracks at the present time are unsatisfactory and expensive, due to their comparatively short life and the frequent need for new ties, with the labor consequent upon replacing them.

Numerous attempts have been made to produce a satisfactory tie of material more durable than wood, but so far none of these have 35 come into extensive use. Ties of concrete and of metal, and also of several combinations of metal and other substances, have all been experimented with, but the defects inherent in them have caused them to be discarded.

40 Among such defects may be enumerated crystallization of metal under repeated impacts, fracture of concrete from the same cause, difficulty of securing the rails to the ties and lack of resiliency in ties causing them to shake 45 out of the ballast.

The invention which forms the subject of the present application, has been made to overcome the difficulties experienced with the various kinds of ties above mentioned. To 50 this end, it consists of a body member in the form of a channel preferably of metal, with resilient blocks therein to absorb vibration, and clamping means for securing the rails

to the ties, the clamping stress being applied by means of wedges.

55

In the drawing, which illustrates one embodiment of this invention:

Fig. 1 represents a plan with portions of rails in place.

Fig. 2, a longitudinal vertical center section;

Figs. 3 and 4, cross sections taken respectively on lines 3 and 4 in Fig. 2, some parts in background omitted, and

Fig. 5, a fragmentary section taken on line 5 in Fig. 2.

Referring to the drawing, the numeral 10 designates the bottom of the body member of the tie while 11 and 12 designate the integrally flanged side members thereof, the three 70 parts forming a channel. This body is preferably of plate metal, though metal in other forms, such as castings, might be used.

Within the channel, and supporting the rails 13, are blocks of resilient material, preferably papier mâché, though wood or other substances might be used if desired. The resilient blocks may each be made in one piece as indicated at 14, or they may each be made of two separate parts, as indicated at 14¹ and 14². In the latter instance, the thinner part 14² is placed directly under the rail and thus takes all the wear resulting from the slight movement and reaction of the rail due to the impacts of the wheels of passing trains. 85 When worn out, the blocks 14² may be easily and cheaply replaced, while the blocks 14¹ remain permanently in place.

Papier mâché is the ideal substance for the rail-supporting blocks because it can be compounded to have just the right properties. Its resiliency and insect-proof properties can be definitely controlled by means of proper ingredients, and it is substantially indestructible by the natural elements under ordinary 95 conditions of use.

The sides 11 and 12 of the tie body are turned outwardly immediately beneath the rail to form outstanding flanges 15. There is thus formed a clearance space between the bottom of the rail and the flanges 15 of the tie, assuming that a rail-supporting block having a thickness equal to the depth of the channel is used. When, after a long period of use, the rail has depressed the block sufficiently so 100 that the rail rests on the flanges, a new block 105

may be put in the place of the old one, at much less expense for material and labor than would be required to replace an entire tie.

On the outer side of each rail, a clamping member 16 having a slight resiliency, is used to in part secure the rail upon the tie. The said clamping member is in general of a Z-shape, one of the horizontal portions being longer than the other, and having an aperture 10 for the passage of the bolt 17 which also passes through an opening 18 in the base 10 of the tie.

A wedge 19 is driven through suitably formed slots in the sides 11 and 12 of the tie. 15 This wedge may be placed with its width inclined to the vertical, so that one edge engages the clamp 16 at the lower bend thereof, where the vertical portion joins that horizontal part that lies substantially in the bottom of the 20 channel.

When the nut 20 on bolt 17 is screwed down tightly, the driving in of the wedge pulls the gripping lug 34 of clamp 16 down firmly upon one flange of the rail and causes the latter 25 to bear upon block 14 or 14¹, as the case may be, bringing the rail and the respective block into intimate contact with each other. To prevent accidental withdrawal of the wedge, a cotter pin 30 may be inserted at the smaller 30 end thereof.

On the inner sides of rails 13, a clamping member 21 which extends across the space between the two rails, and clamps both, may be used. This member is also provided with 35 gripping lugs 34, similar to the corresponding lug on clamp 16. The member 21 may have a considerable upward bulge formed therein. When wedges 32 are driven into place similarly to wedges 19, the completion 40 of the clamping action upon the flanges of the rails is effected. It will be seen that the action of the wedges 32 is two-fold in that they pull the gripping lugs 34 down, and at the same time force the lower corners of member 21 against the blocks 14 and 14¹ thus preventing even a slight shifting of the latter. Above the bulged portion of member 21 may be placed a wedge 31 arranged to bear down 45 upon it, thus causing the extremities 35 of member 21 to spread, thereby assisting the 50 action of wedges 32 along the longitudinal dimension of the tie.

Bolts 27 are provided for two purposes, one of which is to keep the sides 11 and 12 of the tie from spreading when the wedges are driven into place, and the second is to form 55 guards for preventing the vertical portions of the clamps 16 and member 21 from springing outwardly when the lugs 34 are drawn down 60 upon the rails.

When these metal ties are to be used on bridges, viaducts, etc., they may be provided with bolts 24, the heads thereof being placed under the blocks 14 or 14¹, while the bolts may 65 pass through the bridge or viaduct members

(not shown) thus holding the ties securely in place. At present, plate steel is preferred as the material of which these ties are to be made. To keep the steel from rusting, the ties may be heated, and while hot be immersed in 70 a bath of hot asphaltum or the like, and thus be provided with an effectual protective coating.

Ties made in accordance with this invention are designed to be particularly useful in 75 tropical and semi-tropical countries where ordinary wooden ties are often subject to rapid destruction through the ravages of ants and other vermin. In the tie as shown and described herein, it will be noticed that only 80 a very small block surface, such as 40 in Fig. 4, is unprotected by a metal covering and the fact that this small surface is difficult of access and attack by insects, renders the tie 85 practically vermin proof even though untreated wooden blocks should be used for the support of the rails.

While a specific embodiment of this invention is herein shown and described, it is to be clearly understood that all the detailed parts thereof, may, or may not, be shown in the preferred forms, and further, that the preferred forms may be varied from time to time, as the development of this invention and the arts to which it appertains, progress. 90 Therefore, that which forms an essential and characteristic part of this invention will be readily discernible from the claims in which its spirit is generalized.

Having fully described my invention, what 100 I claim is:

1. A tie comprising a channel body member and wedge operated clamping means for securing rails thereto, said clamping means extending continuously from inside of one rail 105 to inside of the other rail, and from each rail outwardly beyond said wedge.

2. A tie comprising a channel body member, resilient rail supporting members in said channel, clamping members having rail-gripping lugs spaced apart from said supporting members, and wedges operatively engaging the said clamping members, said wedges acting to draw said clamping members inwardly and downwardly. 110

3. A tie comprising a channel body member, two-part resilient rail supporting means in said body, and wedge-operated clamping means having gripping lugs for securing rails upon said resilient supporting means, said 115 clamping means extending continuously from inside of one rail to inside of the other rail and from each rail outwardly, the said body member and said clamping means serving together to form a substantially vermin-proof enclosure for said supporting means.

4. In combination, a channel body member, rail clamping members extending longitudinally of said body member, and wedges passing through the sides of said channel, the 120 125 130

width of said wedges being inclined to two principal dimensions of the body member, each wedge having one edge in engagement with a clamping member.

5. A channeled body member, two-part papier mâché rail-supporting members in said body, and gripping members for secur-

ing rails upon said papier mâché supporting members, said gripping members extending continuously from inside of one rail to inside 10 of other rail and from each rail outwardly.

In testimony whereof I sign my name here-
to.

THOMAS DE LA MARE.
